United States Patent Office.

JOHN GIBSON, JR., OF ALBANY, NEW YORK.

Letters Patent No. 98,248, dated December 28, 1869.

RAILROAD-CAR HEATER.

The Schedule referred to in these Letters Patent and making part of the same.

To all whom it may concern:

Be it known that I, JOHN GIBSON, Jr., of the city and county of Albany, State of New York, have invented a new and improved Mode of Warming Rooms of Cars or other Travelling-Conveyances and Buildings; and I do hereby declare that the following is a full and exact description thereof, which will enable others skilled in the art to make and use the same, reference being had to the accompanying drawings, and the letters of reference marked thereon, in which—

Figure 1 is a perspective view of a car or room, with part of floor removed.

Figure 2 is a cross-section view through the centre of a car or room.

Figure 3 is a cross-section of warm-air chamber, under floor, with deflector.

Figure 4 is a cross-section of warm-air chamber, with hooded registers.

The same letters indicate like parts.

The object of this invention is to diffuse, in a perfect manner, a modified, genial, and general warmth throughout the room of rooms of cars, or other travelling-conveyances and buildings, (instead of the old way of warming them from certain points in the room, where the heat is intense,) which is accomplished by conveying the heat from any suitable stove or heater, B, (placed below or outside of the car, conveyance, or room to be heated,) into one or more chambers or spaces, *a a*, formed under the whole or part of the floor *b*, the floor itself forming the top of such chamber, and the lower sheathing (in a car) or ceiling *c* of an under room, forming the bottom, as shown in fig. 2. This floor *b* may be made of metal, either in whole or in part, either cast or "struck up" of sheet-metal, either flat, arched, or corrugated, and when corrugated, rests upon the sills *d*, which form the sides of the chambers *a a*, and the heat is allowed to flow from one chamber to another, through its under corrugations *e*, fig. 2, in the manner indicated by arrows in fig. 1.

When the floor is arched, the heat flows through its arches, and when flat, suitable openings are provided between the chambers *a a* to admit the free flow of heat from chamber to chamber. Suitable metal sheathing may be applied, where necessary, to protect the wood-work.

One or more registers may be placed in the floor *b*, each provided with a flat or "cone-shape" deflector, *h*, or its equivalent, at or near the line of the floor, for the purpose of spreading the heat over the floor.

The deflector *h* is arranged on a standard, working on a suitable support, and can be raised or lowered, thus varying the size of the outlet for the heat, which flows out in the manner indicated by the arrows in fig. 3.

In churches, lecture-rooms, and the like, also in steam-passenger-cars, the metallic floor *b* may run under the seats, and each seat may be provided with a register, *v*, having a fixed hood, *i*, or a register

having a reversible hood, *i'*, which can be thrown either way, as in fig 4, either of which will throw the heat across the floor. These hoods may also answer for foot-rests.

Rooms with side seats, such as lodge-rooms and street-cars, and the like, may have continuous registers *v*, fig. 1, or registers at intervals under the seats, thus being out of the way, and yet giving out heat near the feet of the occupants; and these registers may also be provided with a fixed hood, *i*, or reversible hood, *i'*, fig. 4.

All or any of these registers may be provided with pinch-screws *r*, fig. 1, or their equivalents, for the purpose of holding the registers in a fixed position, when adjusted by the conductor, janitor, or proper person in charge.

The smoke-pipe *p* can be conducted through any chamber *a*, or in any other direction, to a suitable exit.

The advantages of this mode of warming, by constructing and arranging, as described, the various parts of the warming-apparatus, belonging and incidental to this invention, are these:

First, a modified, genial, and even temperature of heat can be secured in every part of a room.

Second, the room can be quickly warmed, close to the floor, by radiation from the floor itself, and the spreading-operation of the deflectors, or the hoods of the registers.

Third, by means of pinch-screws, or their equivalent, the registers are held secure, when set in any desired position, thus avoiding their unintentional displacement, and keeping their control more in the hands of the conductor, janitor, or proper person, than if said registers were not so fastened.

Having described the principles of the construction and arrangement of the several parts of my invention, I do not claim the stove or heater to be used, or its location.

What I claim as my invention, and desire to secure by Letters Patent, is—

1. The metallic floor *b*, corrugated, or otherwise, not perforated, in combination with the hot-air chambers *a a*, substantially as described, and for the purposes set forth.

2. The adjustable deflector or warm-air spreader *h*, also its standard or support, in combination with any register, placed in the floor of any travelling-conveyance or room, substantially as set forth, and for the purposes described.

3. In combination with any warm-air register, a fixed hood *i*, or reversible hood *i'*, for spreading the heat, substantially as described.

4. The pinch-screws *r*, or their equivalent, in combination with the registers *v*, substantially for the purpose set forth and described.

Witnesses: JOHN GIBSON, JR.

C. E. VANSANDT,
J. HARPER GIBSON.
